CLAIM

The ornamental design for a life vest with a foam collar for head and neck support, as shown and described.

DESCRIPTION

FIG. 1.1 is a top, front, right side perspective view of a life vest with a foam collar for head and neck support, showing my new design;

FIG. 1.2 is a bottom, rear, left side perspective view thereof;

FIG. 1.3 is a front elevational view thereof;

FIG. 1.4 is a rear elevational view thereof;

FIG. 1.5 is a left side elevational view thereof;

FIG. 1.6 is a right side elevational view thereof;

FIG. 1.7 is a top plan view thereof; and

FIG. 1.8 is a bottom plan view thereof.

The dot dash-lines shown on the life vest with a foam collar for head and neck support depict stitching that form no part of the claimed design.
